UNITED STATES PATENT OFFICE.

WILLIAM S. VAN SANT, OF OAKLAND, CALIFORNIA, ASSIGNOR OF ONE-THIRD TO EVERETT N. McCUTCHEON AND ONE-THIRD TO ELIJAH M. HIATT, BOTH OF OAKLAND, CALIFORNIA.

ICE-SCRAPER.

1,380,757.

Specification of Letters Patent.

Patented June 7, 1921.

Application filed June 2, 1920. Serial No. 386,121.

To all whom it may concern:

Be it known that I, WILLIAM S. VAN SANT, a citizen of the United States, residing at Oakland, in the county of Alameda 5 and State of California, have invented a new and useful Improvement in Ice-Scrapers, of which the following is a specification.

This invention relates to an ice scraper, 10 and especially to a scraper whereby snow cones or the like may be formed.

One of the objects of the present invention is to provide a simple, substantial and easily operated device whereby ice may be 15 readily reduced by scraping action to a snow-like consistency and simultaneously molded to form cones.

Another object of the invention is to provide a cone shaped molding member, a handle therefor, a pair of scrapers whereby the ice may be readily and quickly disintegrated and delivered to the mold, and in conjunction therewith to provide means for ejecting the material when molded.

25 Further objects will hereinafter appear. The invention consists of the parts and the construction, combination and arrangement of parts as hereinafter more fully described and claimed, having reference to the 30 accompanying drawings, in which—

Figure 1 is a side elevation of the scraper.

Fig. 2 is a plan view of the same.

Fig. 3 is a central vertical longitudinal section of Fig. 1.

35 Fig. 4 is a bottom view of the scraper.

Fig. 5 is a fragmentary view in section showing the removable scraper.

Referring to the drawings in detail, A indicates a cone-shaped molding member to 40 which is suitably secured a tubular shaped handle 2. The molding member is open at one end, as at 3, and is closed at the opposite end by a bottom section 4. This bottom section consists of two inclined plates 4 and 4^a, which are slightly separated to form a cross slot 5. Secured to the bottom section 4 in any suitable manner is a scraper 6. This scraper has a serrated cutting or scraping edge 7, which registers with the slot 45 and directs the ice shavings or particles upwardly in the cone-shaped mold. Formed on one side of the mold is a vertically positioned slot 8. This slot extends from end to end of the molding member and it also is 50 provided with a scraper 9, similar to that

illustrated at 6, that is a serrated cutting edge is provided which also directs the disintegrated material into the mold.

Formed in one side of the mold, adjacent the bottom section, is a slot 10. Projecting therethrough is a spring arm 11, on the inner end of which is secured an ejecting plate 12. The arm 11 forms a portion of a coil spring 14 secured on the tubular handle 2, one end of the spring arm being offset as at 15 to provide a projection which may be readily engaged and depressed by the finger when it is desired to eject the material received by the mold.

The present device is intended for the purpose of reducing ice by scraping or shaving action to a snow-like consistency, and simultaneously molding the disintegrated material to form a cone. This cone is ejected or forced into a cornucopia or like container, 75 and is then flavored by pouring syrup or the like over the same.

In actual operation this is accomplished by first employing one scraper and by drawing the scraper over an ice block in such a manner that a shaving or a disintegrating action will take place. The scraper is pulled toward the operator when employed and the disintegrated material will therefore be forced through one slot or another directly 85 into the mold. Both scrapers may be employed, one at a time, and the snow-like material received by the mold may be tamped by the other hand. A fairly solid snow cone is in this manner produced which 90 may be ejected by depressing the spring arm 11, as depression of said arm forces the plate 12 inwardly and thereby dislodges the snow cone. The snow cone when ejected, as previously described, is received by a cornucopia and may then be flavored to suit the buyer.

The combined scraper and mold here shown is exceedingly simple and substantial, and may be handled by practically any one 100 as comparatively little knowledge is required in the operation of the same. Large scraping surfaces are provided and the operation is therefore comparatively quick. A fresh product is always insured by the buyer as 105 snow cones of this kind melt readily and cannot be kept except in cold storage. The operation of producing the snow cones is, however, so easily and quickly accomplished that the operator does not have to make a 110

supply of the same for sale, but shaves each cone when required.

While certain features of the present invention are more or less specifically illustrated, I wish it understood that various changes in the form and proportion may be resorted to within the scope of the appended claims, similarly that the materials and finish of the several parts employed may 10 be such as the experience and judgment of the manufacturer may dictate or varying conditions may demand.

By referring to Fig. 5 a slight modification of the invention is shown. In this instance a portion of the side and the bottom section is shown as provided with a pocket for the reception of the scraper blade. This is to permit removal of the blade for re-sharpening, etc.

Having thus described my invention, what I claim and desire to secure by Letters Patent is—

1. A combination mold and scraper, comprising a cone shaped mold, a handle therefor, a bottom section in the mold having a transverse slot, a scraper adjacent said slot, an ejector plate adjacent the bottom section of the mold, and means by which said plate may be lifted to eject the contents of the mold.

2. A combination mold and scraper comprising a cone shaped mold, a handle therefor, a bottom section in the mold, a slot formed in one side of the mold extending

from end to end thereof, a scraper adjacent 35 said slot, an ejector plate adjacent the bottom section of the mold, and means by which said plate may be lifted to eject the contents of the mold.

3. A device of the character described, 40 comprising a cone shaped mold member, a bottom section in said mold, a slot formed therein and extending crosswise of the bottom section and a scraper secured to the bottom section and slightly overlapping the 45 slot, a handle for the mold, a spring member secured on the handle and projecting into the mold, and an ejector plate carried by said spring member and adapted to eject contents of the mold upwardly when the 50 spring is compressed.

4. A combination mold and scraper comprising a cone shaped mold, a handle therefor, a bottom in the mold comprising two divergent sections which are spaced to form 55 a slot-like opening between their lower ends, a scraper secured to one section, an ejector plate adjacent the top surface of the other section, and manually operable means by which said ejector plate may be raised for 60 ejecting the contents of the mold.

In testimony whereof I have hereunto set my hand in the presence of two subscribing witnesses:

WILLIAM S. VAN SANT.

Witnesses:

JOHN H. HERRING,
W. W. HEALEY.
